(57) CLAIM

The ornamental design for an air purifier for vehicle, as shown and described.

DESCRIPTION

FIG. 1 is a front elevation view of an air purifier for vehicle in accordance with my design;

FIG. 2 is a rear elevation view of the air purifier for vehicle in accordance with my design;

FIG. 3 is a perspective view of the air purifier for vehicle in accordance with my design;

FIG. 4 is a right-side elevation view of the air purifier for vehicle in accordance with my design;

FIG. 5 is a left-side elevation view of the air purifier for vehicle in accordance with my design;

FIG. 6 is a top plan view of the air purifier for vehicle in accordance with my design; and,

FIG. 7 is a bottom plan view of the air purifier for vehicle in accordance with my design.

In the drawings, the broken lines depict environmental subject matter only and form no part of the claimed design.
